UNITED STATES PATENT OFFICE.

WALTER N. VANCE, OF CHICAGO HEIGHTS, ILLINOIS, ASSIGNOR TO DURAND STEEL
LOCKER COMPANY, OF CHICAGO, ILLINOIS, A CORPORATION OF ILLINOIS.

LOCKER.

Application filed June 2, 1921. Serial No. 474,420.

To all whom it may concern:

Be it known that I, WALTER N. VANCE, a citizen of the United States, residing in Chicago Heights, in the county of Cook and State of Illinois, have invented a new and useful Improvement in Lockers, of which the following is a specification.

This invention relates in general to lockers and has for its object broadly the provision of a new and improved construction of locker which may be conveniently employed to provide the necessary number of locker equipment for a given number of users and through the utilization of a minimum amount of floor space. Lockers embodying my invention contemplate in this regard arrangement of individual coat and hat compartments. Manifestly considerably less width than is ordinarily provided in lockers is sufficient for the mere hanging of a coat or suit of clothes the extra width being ordinarily provided to provide horizontal spacing for the accommodation of hats, shoes, lunches, etc. Lockers embodying my present invention provide for each locker occupant an individual entirely enclosed narrow coat space and in addition thereto a wider compartment for the storing of hats, etc.

A further object of my present invention is a construction of this character wherein the two compartments may be locked closed by a single locking device, although said device may include one, or in fact any number of locking engagements between the door or doors and the locker frame. It will, however, be manifest that from certain aspects of the invention individual locks may be employed for the compartments although it is believed that such arrangement sacrifices some of the advantages.

Another highly important object of the invention is the provision of a locker of the character described, the doors of which will require minimum clearance between lockers in swinging to open position. It is to be borne in mind in this connection that one of the main purposes of the present invention is to effect economy in floor space necessary for a locker occupant, and not only is it desirable that these lockers cover a minimum amount of floor space but also that, when arranged in rows, the rows may be positioned as closely together as will permit use of the lockers by the occupants.

Another and highly important object of

the invention is the provision of a locker of the general character described which will be of pleasing appearance, the use and occupation of which by the occupants will be so manifest as to eliminate any need for special instruction and which will be devoid of complicated, delicate and expensive parts and indeed any parts likely to require frequent repair, replacement or adjustment.

Numerous other objects and advantages of the invention will be apparent as it is better understood from the following description, which, taken in connection with the accompanying drawings, discloses a preferred embodiment thereof.

Referring to the drawings,

Figure 1 is a front elevation of a locker unit embodying my present invention and showing all the compartments closed by the doors; and

Fig. 2 is a similar view showing a coat and a hat compartment open and accessible to the occupant.

For the purpose of illustrating my present invention I have shown on the drawing the at present preferred embodiment of it. This comprises a locker body having side walls 11, back wall 12, top and bottom walls 13 of any usual or preferred construction. These parts constitute what may be termed the outer shell or body and include in themselves such frame and stiffening members as may be thought desirable. Upper and lower horizontal partitions 14 are arranged at appropriate heights to form an upper hat compartment 15 and a lower hat compartment 16. The space between these two partitions 14 is divided in half by a vertical front-to-back partition 17 providing two coat compartments 18, which are relatively narrower than the hat compartments, being in the present instance of half the width of said hat compartments.

There are thus provided two hat and two coat compartments, and the locker unit is adapted to serve two occupants, one of whom will have a hat compartment and an associated coat compartment. In the present instance I provide two elongated doors 19 and 21, each of which is adapted to extend throughout the full length of a coat compartment and across its associated hat compartment. The door 19, for example, is hinged at 22 to extend over a compartment 18 and half of the upper hat compartment 15.

15. At the other side of this upper hat compartment 15 a second hat compartment door 23 is hinged at 24 and is provided with top and bottom marginal flanges 25 adapted to close against the locker top 13 and the front edge of the partition 14 to limit its inward closing movement. This door 23 is provided with a flange 26 at its free or swinging edge which is adapted to lie behind the door 19 when both doors are closed, making it thus impossible to open the door 23 without first opening the door 19. The door 19 is provided with a locking device 27 adapted to engage behind a lock catch 28 appropriately arranged on the partition 17 so that locking of the door 19 in closed position may lock the door 23 as well. While in the present instance I have shown a single locking engagement between the door 19 and the partition 17 it will be manifest that locks embodying a greater number of points of engagement may be employed as for example the locking device of my Patent No. 978,963 dated December 20, 1910.

25. However, it is intended to make the compartments 18 very narrow in a great many instances and in such event it is believed the single engagement will be sufficient.

The door 21 and its companion door 29 are 30 identical in all respects in the present instance with the doors 19 and 23 except that they together cover the lower hat compartment locker 16 and are swung respectively from opposite sides of the frame. It will 35 be manifest that the small door, i. e., the door individualized to a hat locker compartment, moves across the door opening and is there held in position by the main locker door.

40. It is thought that the invention and many of its attendant advantages will be understood from the foregoing description, and it will be apparent that various changes may be made in the form, construction and 45 arrangement of the parts without departing from the spirit and scope of the invention or sacrificing all of its material advantages, the form hereinbefore described being a preferred embodiment thereof.

50. I claim:

1. A locker comprising a relatively narrow coat compartment, and a relatively wide hat compartment associated therewith, a door having locking means and closing the 55 coat compartment and a portion only of the hat compartment, and an additional door for closing the remaining part of the opening into said hat compartment.

2. A locker, comprising a relatively narrow coat compartment, and a relatively wide

65 hat compartment associated therewith, a door having locking means and closing the coat compartment and a portion only of the hat compartment, and an additional door for closing the remaining part of the opening into said hat compartment, said last mentioned door being adapted to be locked closed by the locking of the first mentioned door.

3. A locker, comprising a pair of coat 70 compartments arranged side by side, and a hat compartment above and beneath said pair of coat compartments, and elongated door for closing each coat compartment and a portion of the opening of one of said hat 75 compartments and a second door closing the remaining portion of the opening into each said hat compartment.

4. A locker, comprising a pair of coat 80 compartments arranged side by side, and a hat compartment above and beneath said pair of coat compartments, and elongated door for closing each coat compartment and a portion of the opening of one of said hat 85 compartments, and a second door closing the remaining portion of the opening into each said hat compartment, each said last mentioned door being locked in closed position by its companion first mentioned door.

5. A locker, comprising a pair of relatively narrow coat compartments, and a relatively wide hat compartment above and beneath said pair of coat compartments, said 90 hat compartments extending across the width of said pair of said coat compartments, and door construction individualized to a coat and a hat compartment and 95 adapted to be swung on suitable hinges or pivots, said door construction when swung to open position extending out from the 100 locker substantially only one-half the width of a hat compartment.

6. A locker, comprising a pair of coat compartments, a hat compartment above said pair of coat compartments, a locker door for closing a coat compartment, a second door adapted to swing over the opening of the hat compartment, said first mentioned door being adapted to lock said second mentioned door in closed position.

7. A locker, comprising a pair of coat compartments, a hat compartment above said pair of coat compartments, a locker door for closing a coat compartment, a second door adapted to move over the opening of 115 the hat compartment, said first mentioned door being adapted to lock said second mentioned door in closed position.

WALTER N. VANCE.
